UNITED STATES PATENT OFFICE.

LLOYD L. MURPHY, OF WOODLAKE, CALIFORNIA.

JAR-CLOSURE.

1,294,142.

Specification of Letters Patent. Patented Feb. 11, 1919.

Application filed March 19, 1918. Serial No. 223,402.

To all whom it may concern:

Be it known that I, LLOYD L. MURPHY, a citizen of the United States, residing at Woodlake, in the county of Tulare and State 5 of California, have invented certain new and useful Improvements in Jar-Closures, of which the following is a specification.

This invention relates to improvements in jar closures, more particularly for jars 10 adapted to contain canned fruit, vegetables and the like, and has for one of its objects to improve the construction and increase the efficiency and utility of devices of this character.

15 Another object of the invention is to provide a jar closure including a vent orifice and a holding device for retaining the closure in position and carrying an attachment for closing the vent orifice.

20 Another object of the invention is to provide a device of this character which may be applied without material structural change to jars having different forms of closures.

25 With these and other objects in view, the invention consists in certain novel features of construction, as hereinafter shown and described and then specifically pointed out in the claims; and in the drawings illustrative of the preferred embodiment of the invention—

Figure 1 is a side elevation of a portion of a jar with the improvement applied.

Fig. 2 is a section on the line 2—2 of 30 Fig. 1.

Fig. 3 is a perspective view of the closure holding and vent closing devices detached.

The improved device is applicable more particularly to a jar having an annular closure receiving shoulder and a laterally projecting flange or rib at its open end, and for the purpose of illustration the improved device is shown applied to a jar of this character, a portion of the body of the jar being 45 represented at 10, the annular shoulder at 11 and the encircling or annular rib at 12. The closure of the jar is indicated as a whole at 13 and is formed with a depending margin 14 bearing upon a suitable rubber or like 50 packing ring 15 resting upon the shoulder 11. The closure 13 is provided with a central vent orifice 16, preferably with an inner flaring portion as shown in Fig. 2. Encircling the neck of the jar beneath the rib 12 55 is a wire retaining band 17 united at its ends

as shown at 18 and provided with outwardly directed loops 19—20 at diametrically opposite sides as shown in Fig. 3.

Extending over the closure 13 is a holding rod or member 21 having a down-turned terminal 22 looped at 23 around the loop 19 of the band 17. By this means the member 21 is free to swing upon the loop 19 of the band. Mounted to swing by an eye 24 in the opposite loop 20 is a rod 25 terminating in a hook 26 to engage over the member 21 near its free end. The member 21 is extended near its free end to receive the hook 26, and is preferably formed with an eye 27 at its terminal, to facilitate the handling of the member 21.

Slidably disposed upon the member 21, by ears 28 is a bearing plate 29 having a yieldable packing member 30 attached to its lower face. The member 29 is adapted to be disposed over the vent 16 of the closure 13 with the soft packing 30 engaging over the vent 16, so that when the hook 26 of the member 25 is engaged with the member 21 a pressure will be exerted upon the plate 30 80 against the packing ring 15, and thus "seal" the jar.

When the jar is closed the device 29—30 will effectually "seal" the vent 16 and prevent the entrance of air, but when the closure 13 is released to permit removal of the contents of the jar, the vent will be opened at the same time that the holding device 21 is detached and permit air to enter the jar and destroy the vacuum so as to permit 90 ready release of the closure.

The improved device is simple in construction, can be inexpensively manufactured and adapted without material structural change to jars and closures of various forms.

Having thus described the invention, what is claimed as new is:

1. The combination with a jar including a cover, the neck of the jar being provided with an annular stop rib and the cover with a vent opening, of a retaining band encircling the neck of the jar at said stop rib, a holding member extending across the top of the cover and having one end thereof pivotally connected with the retaining band and its free end provided with a finger piece, a closure slidably mounted on the holding member and adapted to cover the vent opening, and a locking member pivot- 100
105
110

ally mounted on the retaining member and having its free end bent at substantially right angles to the longitudinal plane of said locking member and adapted to engage the holding member at the finger piece thereof.

2. The combination with a jar and cover, the jar being provided with an annular stop rib and the cover being concavo-convex and 10 provided with a centrally disposed vent opening, of a retaining band encircling the jar and bearing against the stop rib, a holding member having one end thereof pivotally connected with the retaining band 15 and its opposite end extended across the top of the cover and provided with a finger piece, a closure slidably mounted on the holding member and including a plate having upstanding perforated lugs for the reception of said holding member and provided on its lower face with a strip of packing material adapted to bear against the convex side of the cover at the vent opening, and a locking member pivotally 20 25 mounted on the retaining band and having its free end provided with an angularly dis-

posed hook adapted to engage the holding member at the finger piece thereof.

3. The combination with a jar including a cover, the jar being provided with a neck 30 having an annular stop rib and the cover being formed with a centrally disposed vent opening, of a retaining band encircling the neck of the jar at said stop rib and provided with diametrically opposite points with 35 laterally extending loops, a substantially L-shaped holding bar having one end thereof engaging one of the loops of the retaining band and its other end bent to form an eye constituting a finger piece, a closure 40 slidably mounted on the bar and adapted to bear against the cover at the vent opening therein, and a locking member comprising a straight rod having one end thereof provided with an eye engaging the other 45 loop on the retaining band and its opposite end bent at substantially right angles to the longitudinal plane of the rod to form a hook adapted to bear against the holding member at the finger piece thereof. 50

In testimony whereof I affix my signature.
LLOYD L. MURPHY.
